(57) **CLAIM**

The ornamental design of a trailer for autonomous delivery, as shown and described.

DESCRIPTION

FIG. 1 is a front, top, left side perspective view of the trailer for autonomous delivery, showing our new design;
FIG. 2 is a front side elevational view thereof;
FIG. 3 is a rear side elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The features shown in broken lines depict environmental structure only and form no part of the claimed design.
